UNITED STATES PATENT OFFICE.

JOHN DEERE CADY, OF MOLINE, ILLINOIS.

CARRIER FOR GOLF-CLUBS.

1,176,031.

Specification of Letters Patent. Patented Mar. 21, 1916.

Application filed September 16, 1915. Serial No. 50,928.

To all whom it may concern:

Be it known that I, JOHN DEERE CADY, a citizen of the United States, residing at Moline, in the county of Rock Island, State of Illinois, have invented certain new and useful Improvements in Carriers for Golf-Clubs, of which the following is a specification, reference being had to the accompanying drawings.

10 The clubs used in the game of golf are, almost without exception, carried around the grounds during the period of play in a bag made especially for that purpose, and when the player employs a considerable 15 number of clubs their combined weight becomes very burdensome, and when a small boy is employed as a caddy such weight frequently constitutes a serious handicap by quickly tiring him out and delaying his 20 progress. If the player himself carries such a heavy bag, as of course is frequently necessary, such weight also impedes his rapid moving over the course, and the fatigue caused by the carrying of so much weight 25 not only detracts from his pleasure but to some extent, it is believed, impairs his effectiveness in the game.

It is the object of my invention to provide new and improved means for the transportation of the golf-clubs of a player over the grounds on which a game is being played, whereby the weight of the player's collection of clubs will not have to be carried or lifted, except possibly at certain places, 35 and thereby the objections above referred to will be avoided. Briefly stated, I accomplish this result by providing a carrier comprising a suitable frame having a pair of supporting wheels by which it may be moved 40 over the ground with but comparatively little effort, such frame, in the preferred construction, being adapted to receive and hold the ordinary bag that is now generally employed for carrying the clubs, but which 45 frame may, if desired, be constructed to receive and hold the clubs without the use of such ordinary club-holding bag.

With either form of frame, I provide a supporting leg, pivoted to the frame and 50 adapted to be swung out therefrom to maintain the bag in an inclined position that will enable the clubs to be readily removed for use or replaced after use—such supporting leg being preferably adjustable.

I accomplish the object stated by the constructions shown in the drawings and hereinafter specifically described.

That which I believe to be new will be pointed out in the claims.

In the drawings:—Figure 1 is a side elevation of the carrier; Fig. 2 is a front elevation of the same; Fig. 3 is a sectional view taken at line 3—3 of Fig. 1; Fig. 4 is a sectional view taken at line 4—4 of Fig. 1; Fig. 5 is a detail of the adjusting means for the supporting leg; Fig. 6 is a detail showing a modification in the construction of the supporting leg; and Fig. 7 is a view in longitudinal central section of a modified form of club-supporting frame.

Referring to the several figures of the drawings in which corresponding reference characters are applied to the same parts, 10 indicates a frame best made of a series of metal rods spaced apart and suitably connected together, and so arranged with respect to each other as to form a semi-cylindrical shaped receptacle adapted to approximately conform to the shape of an ordinary golf-club bag. At its lower end the frame is 15 provided with a rest for the closed end of the bag to abut against—such rest, in the construction shown, being formed by bending or turning the lower end portions of the bars—said rest for the end of the bag being 20 indicated by 11. Secured to one or more of the bars of the frame 10 is a slide 12 which can be locked in different adjusted positions by a set-screw or otherwise, and to this slide is pivotally attached a leg 13 adapted, when 25 it is swung out away from the frame, to support the carrier in an inclined position. Such supporting leg is held in operative position by a brace 14 that may be pivotally connected with the frame and detachably 30 connected with the leg. The lower end of the leg 13 is shown as provided with a head 35 15, which may well be in the form of a rubber cup to aid in preventing rolling movement of the device when resting on a comparatively smooth surface.

16 indicates a pair of wheels, preferably rubber-tired, at opposite sides of the frame 40 10 and near the lower end thereof—such wheels constituting a rolling support for 45 the device to enable it to be readily moved from place to place. Said wheels, in the construction shown, are journaled on a bent

axle 17 that lies wholly outside of the frame 10, but it is obvious that stub axles projecting from the sides of the frame may be employed instead.

5 18 indicates straps adapted to encircle the frame and the golf-club bag carried thereon and, when buckled, to hold such bag and its contained clubs securely in place. Such straps may of course be removably or permanently fastened to the frame, as desired.

10 The golf-bag shown is indicated by A and the ordinary handle therefor by a.

In use, with the bag strapped in place upon the frame 10 and with that side that 15 bears the handle a uppermost, movement of the device over the ground is very readily accomplished by the user grasping the said bag-handle a and pulling up sufficiently to disengage the leg 13 from the ground so that 20 the weight is wholly upon the wheels. Obviously, thereafter the device can be easily pulled along on the wheels, and at any time when it is brought to rest by the operator releasing his hold on the bag-handle the leg 25 will again come in contact with the ground and the bag be held at the angle desired—such angle being fixed by the position to which the slide that carries the leg has been 30 adjusted, as will be understood. By providing for such adjustment different inclinations of the bag are attainable, to adapt the device to the requirements of users of different heights. The outer end of the brace will be adjusted to different positions with 35 respect to the leg as may be required to keep such leg in a substantially vertical position. Any suitable means may be provided for connecting the brace to the leg; in Fig. 1 is shown for this purpose a series of holes 40 in the leg with any one of which the turned end of the brace may engage. If desired, the lower end of the leg 13 may be bifurcated to properly receive and hold a small wheel 19, as shown in Fig. 6. When such 45 construction is employed, the leg 13 would be so adjusted with reference to the frame that the player in taking hold of the bag-handle a would not raise the wheel 19 carried by such leg off of the ground, but would 50 utilize all three wheels as supports when dragging the device from place to place. In such a construction it would be advisable to employ some suitable means for prevent-

ing accidental moving of the device from the place where it was intended to have it rest. 55

In Fig. 7 I have shown a modification wherein the use of the ordinary golf-bag is dispensed with—the frame itself holding the clubs directly. In this construction the frame, indicated by 10a, is made, as in the 60 other case, of light but strong metal bars, and is not semi-cylindrical but substantially cylindrical in shape, and it is provided with two or more heads 20 having aligned openings adapted to receive the shafts or handles 65 of the clubs. In such modified construction the user would grasp the frame itself when dragging it along, or a suitable handle for that purpose could of course be attached to the frame. 70

While I have shown and described the frames in both constructions as made of light and strong metal bars, and while I prefer that construction as tending to produce a light and attractive device, I do not 75 wish to be limited to so making the frame, as it is evident that my invention may be embodied in connection with frames otherwise constructed.

What I claim as my invention and desire 80 to secure by Letters Patent, is—

1. In a device of the class described, the combination with a frame adapted to carry a plurality of golf-clubs, a rolling support for the frame, and means pivotally attached 85 to the frame for supporting the frame in an inclined position, such supporting means being adjustable to vary the inclination of the frame.

2. In a device of the class described, the combination with a frame adapted to carry a plurality of golf-clubs, of a rolling support for the frame, means adjustable with relation to the frame for supporting it in different inclined positions, and means for 95 locking said adjustable supporting means in place.

3. In a device of the class described, the combination with a frame adapted to carry a plurality of golf-clubs, of a rolling support for the frame, a leg connected with the frame for supporting the frame in an inclined position, and means for locking said leg against movement relative to the frame. 100

JOHN DEERE CADY.
